KNIFE HANDLE OR SIMILAR ARTICLE

Ross F. Pollard, Amesbury, Mass., assignor to Towle
Manufacturing Company, Newburyport, Mass.

Filed Sept. 5, 1972, Ser. No. 286,022

Term of patent 14 years

Int. Cl. D7—03

U.S. Cl. D7—150

FIG. 1

FIG. 2

FIG. 3

FIG. 4

FIG. 5

FIG. 6

FIG. 1 is a bottom plan view of a knife handle or similar article showing my new design;

FIG. 2 is a side elevational view as seen from the right of FIG. 1, the opposite side of which is identical;

FIG. 3 is a top plan view;

FIG. 4 is a blade end view;

FIG. 5 is a butt end view; and

FIG. 6 is a sectional view on line 6—6 of FIG. 2.

I claim:

The ornamental design for a knife handle or similar article, substantially as shown and described.
